US0D1069317S

(12) **United States Design Patent** (10) **Patent No.:** **US D1,069,317 S**
(45) **Date of Patent:** **** Apr. 1, 2025**

(54) **BANKING TERMINAL**

(71) Applicant: **HYOSUNG TNS INC.**, Seoul (KR)

(72) Inventors: **Hee Youn Lee**, Gyeonggi-do (KR);
Dong Hee Kim, Seoul (KR); **Jae Min Park**, Gyeonggi-do (KR); **Jae Min Cha**, Gyeonggi-do (KR)

(73) Assignee: **HYOSUNG TNS INC.**, Seoul (KR)

(**) Term: **15 Years**

(21) Appl. No.: **29/773,502**

(22) Filed: **Mar. 10, 2021**

(30) **Foreign Application Priority Data**

Nov. 10, 2020 (KR) 30-2020-0054298

(57) **CLAIM**

The ornamental design for a banking terminal, as shown and described.

DESCRIPTION

FIG. 1 is a perspective view of a banking terminal, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings are included for the purpose of illustrating portions of the banking terminal that form no part of the claimed design.

1 Claim, 7 Drawing Sheets
